UNITED STATES PATENT OFFICE.

JAMES POWERS, OF NEW YORK, N. Y., ASSIGNOR TO POWERS ACCOUNTING MACHINE COMPANY, OF NEW YORK, N. Y., A CORPORATION OF DELAWARE.

PERFORATING-MACHINE.

1,299,022.

Specification of Letters Patent.

Patented Apr. 1, 1919.

Application filed January 13, 1916. Serial No. 71,819.

To all whom it may concern:

Be it known that I, JAMES POWERS, a citizen of the United States, residing in New York, in the county of New York and State of New York, have invented certain new and useful Improvements in Perforating Machines, of which the following is a specification.

This invention relates to accounting machines and especially to foot power operated perforating machines.

Among the main objects of the present invention it is aimed to provide a perforating machine having a keyboard containing one series of keys, a plurality of series of punches, a plurality of series of settable pins, and a carriage operatively connecting said keys with said settable pins, said carriage having a single series of setting pins to be actuated by the keys of said keyboard for setting said settable pins and thereby said punches.

Other objects of the invention are to provide an improved carriage stop, designation character lock, settable pin anchoring means, skip key mechanism, and pin box raising means.

These and other features, capabilities and advantages of the invention will appear from the subjoined detailed description of one specific embodiment thereof illustrated in the accompanying drawings in which—

Figure 1 is a fragmental side elevation partly in section of one complete embodiment.

Fig. 2 is a fragmental front elevation partly in section of the same.

Fig. 2^a is a detail in section of the escapement mechanism.

Fig. 3 is a plan view of the keyboard.

Fig. 4 is a fragmental enlarged section on the line 4—4 of Fig. 2.

Fig. 5 is a fragmental enlarged plan view of the apparatus with the keyboard and carriage removed.

Fig. 6 is a fragmental detail view of the mechanism forming the carriage stop.

Fig. 7 is a section along the line 7—7 of Fig. 6.

Figs. 8 and 9 are fragmental elevational views showing the escapement mechanism in two different operative positions.

Fig. 10 is a fragmental plan view of the escapement mechanism.

Figs. 11 and 12 are fragmental elevational views showing the skip key mechanism in idle and operative positions.

Fig. 13 is a fragmental plan view of a portion of the skip key mechanism.

Figs. 14 and 15 are side elevational and plan views respectively of an element of the designation locking means.

Fig. 16 is a fragmental side elevation showing the settable pin anchoring means.

Fig. 16^a is a fragmental elevational view partly in section of a portion of the designation locking means.

Fig. 17 is a fragmental and elevational view showing the designation locking means.

Fig. 18 is a fragmental elevation similar to Fig. 16 showing the portion of the retractor when actuated.

Fig. 19 is a fragmental plan view showing a portion of the retractor for the anchoring means of the settable pins.

Fig. 19^a is a section along the line 19^a—19^a of Fig. 19.

Fig. 20 is a fragmental end elevation of the anchoring means for the settable pins.

Figs. 21 and 22 are elevational and plan views respectively of the anchoring means for the settable pins.

Figs. 23 and 24 are side and end elevations respectively of the spacer for the designation locks.

Fig. 25 is a perspective view of one of the settable pins.

In the embodiment shown there is provided a main frame M supported on standards S at the upper ends of which bearings 90 are provided, slidably supporting the sliding shaft 11 on which are fixed the cam members 12 and 13 each having an inclined portion 15 at its upper end. The cam member 12 has an elongated lower portion having ears 16 at the front upper ends thereof which are adapted to be engaged by the fingers 17 fixed on the collar 18 pivotally mounted on the shaft 19 which is supported in the bearings 20 formed on the inner upper end of the front standard S. To the collar 18 is also fixed the downwardly extending arm 21 at the lower end of which the treadle 22 is formed. The collar 18 in addition has secured thereto a forwardly extending finger 105 23 on which the pin 24 is formed.

The front and rear of the frame M along its inner sides is provided with vertically

extending guideways 25 in which the vertical portions 26 of the pin box 27 travel. To the upper portion of the pin box 27 the die plate 28 is secured, above which the die plate 29 is secured, the die plate 28 and guide plate 29 each having a plurality of perforations in alignment with one another. In the perforations of the guide plate 29, the lower ends of the punches 30 extend, being normally suspended by their heads 31 which rest on top of the perforated plate 32 fixed to the main frame M. Between the plates 28 and 29, the card to be perforated is disposed, being fed thereto by the picker 33 which travels between suitable guides 34 secured to the pin box 27, the picker having a front extension 35 on which the card to be fed is disposed, and at the front end of which extension a hook portion 36 is formed against which the card to be fed abuts when being positioned on the extension 35. The picker 33 is actuated toward the plates 28 and 29 thereby moving the extension 35 between such plates, 25 by the spring roller 37 over which the band 38 is adapted to be wound, one end being secured thereto and the other end secured to the end of the picker 33, the roller 37 normally maintaining the band 38 wound thereon and winding the band 38 therearound when the picker 33, after having been drawn out to the ends of the guides 34, is released.

For raising the pin box 27, the rollers R 35 are provided pivotally connected thereto to be engaged by the cam members 12 and 13 on the slidable shaft 11.

Above the plate 32, the perforated plate 39 is secured to the frame M through which 40 extend the lower ends of the settable pins 40 whose upper ends extend through the perforated plate 41 also secured to the frame M. The pins 40 are normally maintained in raised position where their shoulders 42 engage the plate 41 by the springs 43 strained between the lower plate 39 and the shoulders 44 of the pins 40. The pins 40 are adapted to be depressed and when so depressed to be locked in depressed position. For locking the pins 40 in depressed position, locking plates 45 are provided which are slidably mounted on the slotted plates 46 and 47 secured to the frame M the ends of the plates 45 being disposed in 55 the slots of such plates 46 and 47. For normally maintaining the plates 45 in their left position, the springs 48 are provided one of the ends of each of said springs being secured to the plate 46 and the other 60 end of each of said springs being secured to the left end of a plate 45. On one face of each of said plates 45 the series of abutments 49 are provided one for each settable pin 40, the abutments in the present 65 instance being staggered to one another for

convenience of arrangement, and each having an inclined cam face at its left end to cooperate with the cam face 50 of a settable pin 40. The lower face of each of said abutments is preferably perpendicular to the path of movement of the pins 40 and forms a stop to enter the recess 51 formed in the pins 40 and cooperate with the shoulders formed by the lower sides of said recesses 51, the recesses 51 being disposed directly above the cam faces 50 of the pins 40. The arrangement of the pins 40 and plates 45 is such that when a pin 40 is depressed its cam face 50 will engage an abutment 49 to move a plate 45 leftward against the tension of its spring 48 until the pin 40 has been depressed far enough so that the engaged abutment 49 is in alignment with the recess 51 of such pin 40 whereupon the tension of the spring 48 will draw the plate 45 rightward to snap the abutment 49 into the recess 51 whereby the pin 40 will be locked in such depressed position until the plate 45 is actuated leftward to withdraw the abutment 49 from the recess 51 to permit the spring 43 of the pin 40 to raise such pin.

For actuating the plates 45 to release the pins 40 a universal plate 52 (Figs. 2, 16, 20) is provided the ends of which are secured to the upper ends of the levers 53 the lower ends of which levers 53 are secured to the shaft 54. One end of the shaft 54 is provided with an arm 55 (Fig. 16) fixed thereto, the free end of which is pivotally connected to the link 56 the lower end of which link is formed into an elongated eye member 57 through which the pin 23 of the finger 24 extends to cooperate therewith. The plate 52 is disposed adjacent to the left ends of the plates 45 so that when the treadle 22 is depressed to raise the pin box 27, it will, due to the clearance of the eye member 57 first raise the pin box 27 and thereupon rock the shaft 54 so that the plate 52 will swing over and actuate the plates 45 rightward so that such plates 45 which had secured certain pins 40 in locked position, will release them and permit them to be extracted by the springs 43.

Certain rows of pins may be preserved for designation characters and to preserve them from repeated resetting, means are provided whereby, when once set, the resetting or retracting of the other pins will not affect such designation characters but permit them to be locked in position for operation. For this purpose, the plate 52 is cut away at 58, so that when the plate 52 is swung the plates 45 opposite to such cut-away portion will 125 not be engaged. In the present instance this cut-away portion 58 is of an extent to pass seven of the plates 45. For the purpose of preserving either one or more of these seven plates against actuation to the exclusion of 130

the others, a bar 59 is secured to the lever 53 which is adjacent to the link 56. The bar 59 has a portion 60 extending up adjacent to the cut-away portion 61 of the plate 52 5 on the side thereof remote from the plates 45. The portion 60 of the bar 59 extends up sufficiently so that the stops 62 may coöperate therewith. The stops 62 each have a short arm 63 and a long arm 64 disposed at 10 right angles thereto, the long arm 64 having two notches 65 and 66 in that edge thereof which is remote from the short arm 63. The stops 62 when positioned so that their notches 65 engage the bar 59, with the short 15 arms extending upward at their left ends, and portions of the long arms 64 disposed on the plate 52 (Fig. 19) will be in position to actuate the plate 45 adjacent thereto whenever the shaft 54 is locked, and when 20 positioned so that their notches 66 engage the bar 59, will permit the rocking of said shaft 54 without actuating the plate 45 disposed adjacent thereto. For securing the 25 stops 62 in position on the plate 45, the anchoring plate 165 (Figs. 23 and 24) is provided which has a series of recesses 166 to receive the stops 62, the ends of the plate 165 being adapted to be secured to the plate 52 and thereby lock the stops between the plate 30 165 and the plate 52, the engagement of one or the other of the recesses 65 or 66 with the bar 59 preventing the longitudinal displacement of the stops 62. Whenever it is desired to change the position of the stops 62, 35 it is only necessary to release the plate 165. To the frame M adjacent to the plates 45, along the left thereof there is secured a rail or track member 67 and along the right thereof there is secured a rail or track member 68. On these rails 67 and 68, a carriage C is slidably mounted. The carriage C comprises essentially a frame member 69 having a single row of setting pins 70 thereon which extend parallel to the plates 45. The upper 40 ends of the pins 70 normally extend a considerable distance above the plate 71 of the carriage C with their collars 72 engaging the lower face of the plate 71, while only a short portion of the pins 70 normally extend 45 below the plate 73 secured to the carriage C, the pins 70 being normally maintained in their raised position by the springs 74 (Fig. 2) strained between the collars 72 and the plate 73. The left end of the frame 50 69 is provided with a bearing 75 for a roller 76 to engage the upper surface of the rail 67, and a downwardly extending arm 77 having a bearing 78 thereon for the roller 79 to engage the lower surface of the rail 67. 55 The right end of the frame 69 is provided with bearings 80 for the groove rollers 81 to engage the upper surface of the rail 68 and a downwardly extending arm 82 having a bearing 83 for the roller 84 to engage the 60 lower surface of the rail 68.

To the rail 68, there is secured a rack 85 with which the gear 86 of the escapement mechanism about to be described meshes. The escapement mechanism comprises essentially a rock shaft 87 mounted in the 70 bearings 88 extending upwardly from the carriage C, a plate 89 fixed to said rock shaft 87 having an upwardly extending end portion 90, a pawl 91 fixed to the right end of the shaft 87 which extends beyond the rail 75 68, one arm of the pawl 91 being provided with a hook portion 92 to engage the ratchet wheel 93 fixed on a collar 98 which is mounted on a stub shaft 94 secured to the frame C on which collar 98 the gear 86 is fixed to 80 rotate with the ratchet wheel 93, the gear 86 being in mesh with the rack 85. The collar 98 extends through the spring housing 96 and is secured to one end of the spring 97, the other end of the spring being secured to the housing 96 by means of which the collar 98 is rotated, in turn to rotate the gear 86 and ratchet wheel 93. The other arm of the pawl 91 is provided with a pin 99 to engage the lower edge of the latch 100 pivotally connected to the frame C, the free end of which is adapted to engage with the teeth of the ratchet wheel 93, the arrangement being such that when the hook portion of the pawl 91 engages the ratchet wheel 93, its pin 99 will raise the latch 100 so that it will come out of engagement with the ratchet wheel 93. For normally maintaining the pawl 91 out of engagement with the ratchet wheel 93, and thereby maintaining the latch 100 in 95 engagement with the ratchet wheel 93, a spring 101 connects the pin 102 of the latch 100 with the frame C, exercising a downward pressure thereon. 100 The arrangement of the foregoing is to 105 permit the advancement of the carriage C every time the upwardly extending portion 90 of the plate 89 is actuated. Secured to the rear upper end of the frame M (Fig. 1) is provided a shaft 102 to 110 which a plurality of links 103 are pivotally connected, the upper ends of which are pivotally connected to a like plurality of elongated bars 104 which extend longitudinally of the path of movement of the carriage C, 115 a bar 104 being provided for each pin 70, and each disposed above one of said pins 70 so that the actuation of said bar 104 will depress the pin 70 disposed therebelow. Besides the bars 104 for the pins 70 there is 120 one additional bar 104 to actuate a spacer or skip key mechanism. The front ends of the bars 104 are pivotally connected to the upper ends of the links 105 parallel to the 125 links 103 and pivotally connected at their lower ends to the shaft 106 which is secured to the front upper end of the bracket 107 extending from the front upper end of the frame M. To each of the bars 104 there is secured an upwardly extending key por- 130

tion 108 at the upper end of which is secured a button 109 which may be provided with a suitable character to indicate the character to which it is connected. To suitably inclose the mechanism, the cover 110 is provided which is secured to the upper ends of the frame M. For returning the bars 104 and therewith the keys 109 to their normal raised position limited by the abutment 115, the springs 124 are provided coiled around the shaft 102 with one end secured to the links 103 and the other end to the frame M.

To form a spacer or skip key mechanism, there is provided a bar 111 (Fig. 13) having a plurality of notches 112 which are spaced from one another a distance corresponding to the distance the carriage C is permitted to travel whenever the ratchet wheel 93 is actuated one tooth space. The recesses 112 are formed to receive the stop plates 113 which are slidably mounted on a shaft 95 and have a long downwardly extending arm 114 to extend downward below the bar 111. The bar 111 is disposed parallel to the bars 104 and above the slide of the carriage C where the rack 85 is disposed. For coöperating with the stop plates 113 a lever plate 116 is pivotally connected to the upwardly extending portion 117 of the carriage C, the pivotal connection being preferably disposed between the bars 104 and the bar 111. The arm 118 of the lever plate 116 is disposed below the path of movement of the spacer bar 104 and adapted to be engaged thereby when such spacer bar 104 is depressed. The other arm 119 of the lever plate 116 is provided with an upwardly extending portion 120, the path of movement of which when the arm 118 is depressed, will be obstructed by the downwardly extending arm 114 of a stop plate 113. The lever plate 116 is normally maintained out of engagement with the plate 113 by the spring 122 strained between its arms 118 and the upward extension 117, the lower right hand corner of the arm 118 extending at right angles to the arm 119 to form the pin 121 and being adapted to engage the pin 150 in the latch 100. The arrangement is such that when the spacer bar 104 is depressed it will engage the arm 118 whereby the pin 121 will engage the pin 150 to raise the latch 100 out of engagement with the ratchet wheel 93, so that both the pawl 91 and the latch 100 will be raised out of engagement with the ratchet wheel 93 and permit its free rotation, and thereby the free movement of the carriage C. Such movement of the carriage C will continue until the upwardly extending portion 120 of the lever plate 116 strikes the downwardly extending arm 114 of a stop plate 113 and then, upon the release of the spacer bar 104, the latch 100

will be retracted by the spring 101 into engagement with the ratchet wheel 93 and the lever plate 116 retracted by the spring 122.

When some of the rows of settable pins 40 are not to be used and such pins 40 are generally those at the front end of the machine, and it is therefore unnecessary for the carriage to travel across all of the pins 40, an adjustable stop (Figs. 3, 6 and 7) is provided comprising a bearing 123 secured to the bracket 107, through which the split cylindrical clamping portion 124 extends. The portion 124 is provided with external screw threads at one end on which the nut 125 is adapted to be secured to draw the portion 124 securely into the bearing 123, the outer faces of the portion 124 being tapering, so that the action of the nut 125 will also draw the split portions of the portion 124 tightly together. The portion 124 is provided with a bore to accommodate the rod 126, the rod 126 being provided with a series of notches 127 along one side thereof with which the inner end of the pin 128 cooperates to lock the rod 126 in place. The pin 128 is disposed in the extension 129 formed on the split portion 124 extending laterally therefrom, and has a head 130 on its inner end between which and the nut 131 closing the extension 129, a spring 132 is strained to normally impinge the inner end of the pin 128 into one of the notches 127 of the rod 126. On the outer end of the pin 128, a finger piece 133 is provided whereby the pin may be engaged to withdraw the pin 128 from engagement with the notches 127. The outer or front end of the rod 126 is bent to form a handle 134 (Fig. 3) and the inner end forms a stop against which the frame 69 of the carriage C may strike and be stopped.

The operation of the machine is as follows:

The cards to be fed in are disposed on the extension 35, whereupon the release of the picker 33 will permit the spring roller 37 to convey the card into the machine between the plates 28 and 29. Thereupon keys 109 are manipulated, whose bars will engage setting pins 70 of the carriage C which in turn will depress settable pins 40 disposed underneath and such depressed settable pins 40 will in turn be locked by one of the locking plates 45 in depressed position, simultaneously therewith the depression of the aforesaid bars 104 will, when depressing the setting pins 70, also engage the upwardly extending portion 90 of the rock plate 89 thereby actuating the escapement mechanism to advance one tooth space upon the release of a key 109 and the bar 104 and the pin 70 depressed will be raised by the springs 124 and 74 respectively but the pin 40 depressed will remain locked. Upon the next

impression of a character key 109 the settable pin 40 of another row will be locked in the manner just explained. When it is desired to move the carriage to the next column of data, the spacer key is depressed and the ratchet wheel 93 will be freed from both the pawl 90 and the latch 100 so that its spring 97 will be free to move the carriage C until its lever plate 116 strikes a stop plate 113 previously set on the bar 111 and upon the release of the spacer key, the latch 100 will again engage the ratchet wheel 93 to lock the carriage C in position. Then the character keys 109 may again be manipulated to set the settable pins 40 of other rows and upon completion of said column, the spacer key may again be actuated to advance the carriage to the next column of figures, it being understood that the stop plates 113 will be positioned on the bar 111 before starting the operation of the machine. The aforesaid operation may continue until all of the data has been set, whereupon the treadle 22 may be depressed, and the pin box 27 raised by the engagement of the cams 12 and 13 with the rollers R; the depression of the treadle 22 also actuates the link 56 to actuate the locking plates 45 thereby to release the settable pins 40. If any of the rows of figures are designation characters which are common to a plurality of cards to be perforated, the stops 62 will have been previously set so that the locking plates 45 of such designation characters will not be released when pressing the treadle 22. When the pin box 27 is so raised by the treadle 22 the punches 30 of the pin box which are in alinement with pins 40 that have been locked in depressed position will perforate the card disposed between the plates 28 and 29. Then upon the release of the treadle 22, the pin box 27 will descend to normal position, permitting the punches 30 to be withdrawn from the card perforated, whereupon the picker 33 is withdrawn to remove the card perforated. The machine then is ready for a second perforation. It will be understood that when there are designation characters common to a plurality of cards, such characters will be disposed on the front end of the card, so that the carriage C need not pass over the rows of pins corresponding to the designation characters, for which purpose the stop rod 126 is provided which will prevent the carriage C to be moved all the way to the front end of the machine but stop before arriving at such front end. Obviously as many rows of pins may be used for designation characters as desired, the stop rod 126 being adjustable to be set to correspond with whatever number of rows of pins are used.

It is obvious that various changes and modifications may be made to the details of

construction without departing from the general spirit of the invention.

I claim:

1. In a perforating machine, the combination with a frame, of a plurality of rows of settable pins, a carriage disposed to move transversely of said settable pins, a single row of setting pins on said carriage adapted successively to register with the several rows of settable pins, means for actuating said setting pins, the settable pins being moved and set by said setting pins when the setting pins are actuated, a pin box, means for vertically reciprocating said pin box, a plurality of punches carried by said pin box, and a card support on said pin box, the punches of said pin box being actuated by the actuated settable pins when said pin box is raised thereby to perforate a card supported on said card support.

2. In a perforating machine, the combination with a frame, of a plurality of rows of settable pins, a carriage disposed to move transversely of said settable pins, a single row of setting pins on said carriage adapted successively to register with the several rows of settable pins, means for actuating said setting pins, the settable pins being actuated by said setting pins when actuated, means for locking said settable pins in actuated position, a pin box, means for vertically reciprocating said pin box, a plurality of punches carried by said pin box, a card support on said pin box, the punches of said pin box being actuated by the actuated settable pins when said pin box is raised thereby to perforate a card supported on said card support.

3. In a perforating machine, the combination with a frame, of a plurality of rows of settable pins, a carriage disposed to move transversely of said settable pins, a single row of setting pins on said carriage adapted successively to register with the several rows of said settable pins, means for actuating said setting pins, the settable pins being actuated by said setting pins when so actuated, there being recesses in sides of said settable pins, cam faces adjacent of said recesses, rocking plates, lugs on one of the faces of said plates, the cam faces of those settable pins which are actuated engaging certain of said lugs and thereby rocking said plate of one set until the recesses of said settable pins register with said lugs, means being provided for normally maintaining the plates in a position where the lugs are in the path of movement of said settable pins, and means for releasing said plates thereby to permit the settable pins to be retracted.

4. In a perforating machine, the combination with a frame, of a plurality of rows of settable pins, a carriage disposed to move transversely of said settable pins, a single row of setting pins on said carriage adapted

to successively register with the several rows of said settable pins, means for actuating said setting pins, the settable pins being actuated by said setting pins when actuated, 5 a pin box, means for vertically reciprocating said pin box, a plurality of punches carried by said pin box, and a card support slidably mounted on said pin box, means for normally retaining said card support into position 10 to permit the card supported thereon to be perforated, said retaining means permitting the withdrawal of said card support when desired to either remove a card or to insert a fresh card, the punches of said pin box being actuated by the said settable pins when said pin box is reciprocated thereby to perforate a card supported on said card support.

5. In a perforating machine, the combination 20 with a frame, of a plurality of rows of settable pins, a carriage disposed to move transversely of said settable pins, a single row of setting pins on said carriage adapted successively to register with the several rows 25 of settable pins, means for actuating said setting pins, the settable pins being actuated by said setting pins when actuated, a pin box, means for vertically reciprocating said pin box, a plurality of punches carried 30 by said pin box, a card support on said pin box, the punches of said pin box being actuated by the actuated settable pins when said pin box is raised thereby to perforate a card supported on said card support, a stationary 35 keyboard having a plurality of keys, an actuatable bar connected to each of said keys, each of said bars being disposed longitudinally above the path of movement of a setting pin of the carriage, so that the actuation of a key will actuate its actuatable bar to actuate a setting pin on said carriage at any position in its path of movement.

6. In a perforating machine, the combination 45 with a frame, of a plurality of rows of settable pins, a carriage disposed to move transversely of said settable pins, a single row of setting pins on said carriage adapted successively to register with the several rows 50 of settable pins, means for actuating said setting pins, the settable pins being actuated by said setting pins when actuated, means for locking said settable pins in actuated position, a pin box, means for vertically reciprocating said pin box, a plurality 55 of punches carried by said pin box, a card support on said pin box, the punches of said pin box being actuated by the actuated settable pins when said pin box is raised thereby to perforate a card supported on said card support, the settable pins at one end of 60 the group serving as designation characters which are common to a plurality of cards to be perforated, means for preventing the unlocking of such designation settable pins, 65 means for limiting the movement of said

carriage so that it will not move across such designation settable pins.

7. In a perforating machine, the combination with a frame, of a plurality of rows of settable pins, a carriage disposed to move 70 transversely of said settable pins, a single row of setting pins on said carriage adapted successively to register with the several rows of settable pins, means for actuating said setting pins, the settable pins being actuated 75 by said setting pins when actuated, means for locking said settable pins in actuated position, a pin box, means for vertically reciprocating said pin box, a plurality of punches carried by said pin box, a card support on said pin box, the punches of said pin box being actuated by the actuated settable pins when said pin box is raised thereby to 80 perforate a card supported on said card support, the settable pins at one end of the 85 group serving as designation characters which are common to a plurality of pins to be perforated, means for preventing the unlocking of such designation settable pins, means for limiting the movement of said 90 carriage so that it will not move across such designation settable pins, said limiting means comprising a bearing formed in said frame, a stopping rod extending through said bearing, one end of which will serve as 95 the abutment against which the carriage strikes in its limit of movement, and means for anchoring said bar to said bearing at whatever position it is set according to the 100 number of designation characters.

8. In a perforating machine, the combination with a plurality of punches, of a plurality of settable pins for obstructing the path of movement of the punches designed to perforate, there being recesses in the sides of 105 said settable pins, cam faces adjacent to said recesses, locking plates, lugs on one of the faces of said plates to be engaged by the cam faces of the recesses of those settable pins which are set, means for normally maintaining the plates in a position where the lugs are in the path of movement of said settable pins, and means for releasing said plates thereby to permit the settable pins to be retracted.

9. In a perforating machine, the combination with a plurality of punches, of a card support mounted to slide transversely to the path of movement of the punches, and means for normally retaining said card support in position to permit the card supported thereon to be perforated by said punches, said retaining means permitting the withdrawal of said card support when desired to either remove a card or to insert a fresh one.

10. In a perforating machine, the combination with a pin box, of a plurality of punches slidably mounted in said pin box, rollers on said pin box, a slidable shaft, cams on said shaft for engaging said rollers, means for 120 125 130

actuating said shaft to bring said cams into engagement with said rollers and thereby raise said pin box, and means settable mounted to be disposed in the path of movement of said punches so that when said pin box is raised by said cams the obstructed punches will perforate.

11. In a perforating machine, the combination with a frame, of a pin box reciprocably mounted in said frame, of a plurality of punches slidably mounted in said pin box, rollers on said pin box, a shaft slidably mounted on said frame, cams on said shaft for engaging said rollers to raise said pin box, a lever fulcrumed in said frame and operatively connected to one end of said shaft, a treadle on the other end of said lever whereby said lever may be actuated and thereby actuate said shaft to raise said pin box, and means settable mounted to be disposed in the path of movement of said punches so that when said pin box is raised by said cams the obstructed punches will perforate.

12. In a perforating machine, the combination with a frame, of a plurality of rows of settable pins, a carriage disposed to travel transversely of said settable pins, a single row of setting pins on said carriage corresponding to a row of settable pins, a stationary keyboard having a plurality of keys, an actuatable bar connected to each of said keys, each of said bars being disposed longitudinally above the path of movement of a setting pin of the carriage so that the actuation of a key will actuate its actuatable bar to engage and actuate a setting pin on said carriage at any position in its path of movement.

13. In a perforating machine, the combination with a frame, of a plurality of rows of settable pins, a carriage disposed to travel transversely of said settable pins, a single row of setting pins on said carriage corresponding to a row of settable pins, a stationary keyboard having a plurality of keys corresponding in number to the number of setting pins, and means for operatively connecting said keys with said setting pins only while said setting pins are positioned above the several rows of settable pins.

14. In a perforating machine, the combination with a frame, of a plurality of rows of settable pins, a carriage disposed to travel transversely of said settable pins, a single row of setting pins on said carriage corresponding to a row of settable pins, a stationary keyboard having a plurality of keys corresponding in number to the number of setting pins, means for operatively connecting said keys with said setting pins only while said setting pins are positioned above the several rows of settable pins, and an escapement mechanism whereby said carriage will be simultaneously actuated the

distance of one row of settable pins from another every time a setting pin is actuated.

15. In a perforating machine, the combination with a frame, of a plurality of rows of settable pins, a carriage disposed to travel transversely of said settable pins, a single row of setting pins on said carriage corresponding to a row of settable pins, a stationary keyboard having a plurality of keys, an actuatable bar connected to each of said keys, each of said bars being disposed longitudinally above the path of movement of a setting pin of the carriage so that the actuation of a key will actuate its actuatable bar to actuate a setting pin on said carriage at any position in its path of movement, a rock shaft disposed on said carriage adjacent to said row of setting pins, a rock plate secured thereto, means for normally maintaining said rock plate in raised position, and an escapement mechanism operatively connected to said rock shaft so that the carriage will be simultaneously actuated the distance from one row of settable pins to another every time a setting pin is actuated, the actuation of one of said bars by said keys simultaneously actuating the rock plate.

16. In a perforating machine, the combination with a frame, of a plurality of rows of settable pins, a carriage disposed to travel transversely of said settable pins, a single row of setting pins on said carriage corresponding to a row of settable pins, a stationary keyboard having a plurality of keys, an actuatable bar connected to each of said keys, each of said bars being disposed longitudinally above the path of movement of a setting pin of the carriage so that the actuation of a key will actuate its actuatable bar to actuate a setting pin on said carriage at any position in its path of movement, an escapement mechanism whereby said carriage will be simultaneously actuated the distance from one row of settable pins to another every time a setting pin is actuated, said escapement mechanism comprising a ratchet wheel, a latch, means for normally maintaining said latch in contact with said ratchet wheel to lock the same against movement, a pawl for engaging said ratchet wheel, and a pin on said pawl adapted to release said latch from said ratchet wheel whenever said pawl is actuated to engage said ratchet wheel and permit a one tooth space movement of said carriage.

17. In a perforating machine, the combination with a frame, of a plurality of rows of settable pins, a carriage disposed to travel transversely of said settable pins, a single row of setting pins on said carriage corresponding to a row of settable pins, a stationary keyboard having a plurality of keys, an actuatable bar connected to each of said keys, each of said bars being disposed longitudinally above the path of movement of

- a setting pin of the carriage so that the actuation of a key will actuate its actuatable bar to actuate a setting pin on said carriage at any position in its path of movement, an 5
 5 escapement mechanism whereby said carriage will be simultaneously actuated the distance from one row of settable pins to another every time a setting pin is actuated, said escapement mechanism comprising a 10 ratchet wheel, a latch, means for normally maintaining said latch in contact with said ratchet wheel to lock the same against movement, a pawl for engaging said ratchet wheel, a pin on said pawl adapted to release said latch from said ratchet wheel whenever said pawl is actuated to engage 15 said ratchet wheel and permit a one tooth space movement of said carriage, and a skip key mechanism for raising said latch so that 20 said carriage may freely travel more than one tooth space.
18. In a perforating machine, the combination with a frame, of a plurality of rows of settable pins, a carriage disposed to travel 25 transversely of said settable pins, a single row of setting pins on said carriage corresponding to a row of settable pins, a stationary keyboard having a plurality of keys corresponding in number to the number of 30 setting pins, means for operatively connecting said keys with said setting pins while said setting pins are successively positioned above the several rows of settable pins, means for propelling said carriage in one 35 direction, means for normally anchoring said carriage against movement, and a skip key mechanism for releasing said anchoring means so that said carriage may freely travel.
- 40 19. In a perforating machine, the combination with a frame, of a plurality of rows of settable pins, a carriage disposed to travel transversely of said settable pins, a single row of setting pins on said carriage corresponding to a row of settable pins, a stationary keyboard having a plurality of keys corresponding in number to the number of 45 setting pins, means for operatively connecting said keys with said setting pins while said setting pins are successively positioned above the several rows of settable pins, means for propelling said carriage in one direction, means for normally anchoring said carriage against movement, a skip key 50 mechanism for releasing said anchoring means so that said carriage may freely travel, and means for stopping said carriage at predetermined points when actuated by said skip key mechanism.
- 55 60 20. In a perforating machine, the combination with a plurality of punches, of a plurality of settable pins for obstructing the path of movement of the punches designed to perforate, there being recesses in the sides

of said settable pins, cam faces adjacent to 65 said recesses, locking plates, lugs on one of the faces of said plates to be engaged by the faces of the recesses of those settable pins which are set, means for normally maintaining the plates in a position where 70 the lugs are in the path of movement of said settable pins, means for normally maintaining said settable pins in raised position, a rock shaft, and a rock plate on said rock shaft adapted to engage the locking plates 75 when said rock plate is rocked thereby actuating said locking plates so that the settable pins locked thereby will be liberated to freely move into their raised position.

21. In a perforating machine, the combination with a plurality of punches, of a plurality of settable pins for obstructing the path of movement of the punches designed to perforate, there being recesses in the sides of said settable pins, cam faces adjacent to 80 said recesses, locking plates, lugs on one of the faces of said plates to be engaged by the faces of the recesses of those settable pins which are set, means for normally maintaining the plates in a position where the lugs 85 are in the path of movement of said settable pins, means for normally maintaining said settable pins in raised position, a rock shaft, a rock plate on said rock shaft adapted to engage the locking plates when said rock 90 plate is rocked thereby actuating said locking plates so that the settable pins locked thereby will be liberated to freely move into their raised position, a lever fulcrumed in said machine, an arm on said rock shaft, a 95 link connecting said arm with said lever, and a treadle on said lever whereby said lever may be actuated to rock said rock shaft.

22. In a perforating machine, the combination with a frame, of a pin box reciprocably mounted in said frame, a plurality of punches slidably mounted in said pin box, a plurality of settable pins for obstructing the path of movement of those punches designed 105 to perforate, means for normally maintaining said settable pins in raised position, means for actuating said pins into set position or punch obstructing position, locking plates 110 for anchoring said settable pins in obstructing position, a rock shaft, a rock plate on said shaft for actuating said locking plates to liberate settable pins locked thereby to permit them to rise, rollers on said pin box, a shaft slidably mounted in said frame, cams 115 on said shaft for engaging said rollers to raise said pin box, a lever fulcrumed in said frame and operatively connected at one end to said shaft, a treadle on the other end of said lever whereby said lever may be actuated and thereby actuate said shaft to raise said pin box, an arm on said rock shaft, and a link connecting said arm with said lever 120 125

so that said locking plates may be simultaneously actuated to release said settable pins when raising said pin box to effect perforation.

- 5 23. In a perforating machine, the combination with a plurality of punches, of a plurality of settable pins for obstructing the path of movement of the punches designed to perforate, means for normally maintaining said settable pins in raised position, locking plates for anchoring said settable pins in punch obstructing position, means for normally maintaining the plates in a settable pin anchoring position, a locking plate being provided for each row of punches corresponding to a row of data, means for actuating said locking plates after each perforation to permit the anchored settable pins to rise, and designation anchoring means whereby locking plates corresponding to rows of designation characters will not be actuated to release settable pins after each perforation.

24. In a perforating machine, the combination with a plurality of punches, of a plurality of settable pins for obstructing the path of movement of the punches designed to perforate, means for normally maintaining said settable pins in raised position, locking plates for anchoring said settable pins in punch obstructing position, means for normally maintaining said plates in settable pin anchoring position, a locking plate being provided for each row of punches corresponding to a row of data, a rock shaft, a rock plate on said shaft positioned to actuate said locking plates whereby to liberate the settable pins anchored thereby, there being a cut-away portion in said rock plate disposed adjacent to certain of said locking plates corresponding to designation character rows, so that the rocking of the rock plate will not actuate such designation character locking plates.

45 25. In a perforating machine, the combination with a plurality of punches, of a plurality of settable pins for obstructing the path of movement of the punches designed to perforate, means for normally maintaining said settable pins in raised position, locking plates for anchoring said settable pins in punch obstructing position, means for normally maintaining said plates in settable pin anchoring position, a locking plate being provided for each row of punches corresponding to a row of data, a rock shaft, a rock plate on said shaft positioned to actuate said locking plates whereby to liberate the settable pins anchored thereby, there being a cut-away portion in said rock plate disposed adjacent to certain of said locking plates corresponding to designation character rows, so that the rocking of the rock plate will not actuate such designation character locking plates, and stop bars to be se-

cured to said rock plate at such cut-away portion to obstruct those locking plates not to be used for designation characters.

26. In a perforating machine, the combination with a frame, of a plurality of rows of settable pins, a carriage disposed to travel transversely of said settable pins, a single row of setting pins on said carriage corresponding to a row of settable pins, a stationary keyboard having a plurality of keys corresponding in number to the number of setting pins, means for operatively connecting said keys with said setting pins while said setting pins are successively positioned above the several rows of settable pins, and means for limiting the movement of said carriage so that the row of setting pins need not be moved into registration with certain rows of settable pins.

27. In a perforating machine, the combination with a frame, of a plurality of rows of settable pins, a carriage disposed to travel transversely of said settable pins, a single row of setting pins on said carriage corresponding to a row of settable pins, a stationary keyboard having a plurality of keys corresponding in number to the number of setting pins, means for operatively connecting said keys with said setting pins while said setting pins are successively positioned above the several rows of settable pins, a bearing on said frame, a rod slidably mounted in said bearing and extending parallel to the path of movement of said carriage, one end of which may be disposed to limit or obstruct the movement of said carriage so that the row of setting pins may not be moved into registration with certain rows of settable pins.

28. In a perforating machine, the combination with a frame, of a plurality of rows of settable pins, a carriage disposed to travel transversely of said settable pins, a single row of setting pins on said carriage corresponding to a row of settable pins, a stationary keyboard having a plurality of keys corresponding in number to the number of setting pins, means for operatively connecting said keys with said setting pins while said setting pins are successively positioned above the several rows of settable pins, a bearing on said frame, a rod slidably mounted in said bearing and extending parallel to the path of movement of said carriage, one end of which may be disposed to limit or obstruct the movement of said carriage so that the row of setting pins may be moved into registration with certain rows of settable pins, there being graduations on said rod, and a pin resiliently mounted in such bearing to engage said graduations whereby said rod may be set in any of a series of predetermined positions to limit the movement of said carriage.

29. In a card perforating machine, the

- combination with a plurality of rows of settable pins, of a carriage disposed to move transversely of said settable pins, a single row of setting pins on said carriage adapted 5 successively to register with the several rows of settable pins, means for actuating said setting pins, the settable pins being actuated by said setting pins when actuated, punches, means for actuating said punches into engagement with said settable pins to be operated thereby, means for locking said settable pins in actuated position, one portion of the settable pins serving as designation characters which are common to a plurality 10 of the cards to be perforated, means for preventing the unlocking of such designation settable pins, and means for locking the movement of said carriage so that it will not move across such designation settable pins.
30. In a perforating machine, the combination of a plurality of settable means; means coöperating therewith for effecting punching; setting means adapted to be brought into association with successive settable means for actuating the latter; and means adapted to actuate the setting means and to remain substantially out of contact with and disconnected from the setting means and stationary while the setting means 35 is moved from association with one settable means to another.
31. In a perforating machine, the combination of a plurality of settable means; means coöperating therewith for effecting 40 punching; setting means adapted to be brought into association with successive settable means for actuation of the latter; and a set of keys adapted to actuate the setting means and to be free of connection with the settable means.
32. In a perforating machine, the combination of a plurality of settable means; punches coöperating therewith for effecting punching; setting means adapted to be 45 brought into association with successive settable means for actuating the latter; and means adapted to actuate the setting means and adapted to remain substantially free from connection with the settable means as 50 the setting means is moved from association with one settable means to another.
33. In a perforating machine, the combination of a plurality of settable means; punches coöperating therewith for effecting 55 punching; setting means adapted to be brought into association with successive settable means for actuating the latter; and a set of keys provided with connecting means adapted to actuate the setting means and 60 adapted to remain substantially free from contact with the setting means when the setting means is moved from association with one settable means to another.
34. In a perforating machine, the combi-

nation of a plurality of settable means, a plurality of punches; means for actuating said punches into engagement with the settable means, whereby the punches are operated; a plurality of setting means adapted to be moved from association with one settable means to association with another settable means; actuating means adapted to actuate said setting means and adapted to remain substantially out of contact with the setting means while the setting means 75 are moved from one of said associations to another.

35. In a perforating machine, the combination of a plurality of settable pins; a plurality of punches; means for actuating the punches into coöperation with the settable pins whereby punching may be effected; a row of setting pins adapted to be brought into association with the successive settable pins and to move and set said settable pins; 85 and keys operatively connected to the corresponding setting pins for actuating the latter, said keys being adapted to remain out of contact with and free from connection with the setting pins as the setting pins 90 move from association with one settable pin to another.

36. In a perforating machine, the combination of a plurality of rows of settable pins; a plurality of punches; means for actuating the punches into engagement with the settable pins whereby punching may be effected; a carriage above said settable pins and adapted to move into association with the successive rows of settable pins; a row of setting pins carried on the carriage and adapted to be brought into association with the successive rows of settable pins and each setting pin to move and set its associated settable pin; and a set of keys, each key 105 being operatively connected to a corresponding setting pin, said set of keys being adapted to remain substantially out of contact with and free from connection with the setting pins as the setting pins move from 110 association with one row of settable pins to another.

37. In a perforating machine, the combination of a plurality of rows of settable pins; a plurality of rows of punches; means for actuating the punches into engagement with the settable pins whereby punching may be effected; a carriage above said settable pins and adapted to move step-by-step into association with the successive rows of 120 settable pins; a single row of setting pins carried on the carriage and adapted to register with the successive rows of settable pins and to move and set the registering setting pin; a set of keys, each key corresponding to a setting pin, said keys being adapted to remain disconnected from the setting pins as the setting pins move from 125

registry with one row of settable pins to another; key operated means operatively connecting each key with the corresponding setting pin; and means for propelling said carriage in one direction with a step-by-step motion.

38. In a perforating machine, the combination of a plurality of rows of settable pins; a plurality of rows of punches; means for actuating the punches into engagement with the settable pins, whereby punching may be effected; a carriage above said settable pins and adapted to move step-by-step into association with the successive rows of settable pins; a single row of setting pins carried on the carriage and adapted to register with successive rows of settable pins, and to move and set the registering setting

pin; a set of keys, each key corresponding to a setting pin; said keys being adapted to remain disconnected from the setting pins as the setting pins move from registry with one row of setting pins to another; key operated means operatively connecting each key with the corresponding setting pin; means for propelling said carriage in one direction step-by-step; means for anchoring said carriage against movement; a skip key mechanism for releasing said anchoring means so the carriage may travel free.
